US0D1099658S

(12) **United States Design Patent** (10) **Patent No.:** **US D1,099,658 S**
(45) **Date of Patent:** **** Oct. 28, 2025**

(54) **WRENCH**

(71) Applicant: **Milwaukee Electric Tool Corporation**,
Brookfield, WI (US)

(72) Inventors: **Joseph M. DeBaker**, Greenfield, WI
(US); **Andrew M. Tuchscherer**,
Wauwatosa, WI (US); **Steven W.
Hyma**, Milwaukee, WI (US)

(73) Assignee: **Milwaukee Electric Tool Corporation**,
Brookfield, WI (US)

(**) Term: **15 Years**

(21) Appl. No.: **29/828,165**

(22) Filed: **Feb. 24, 2022**

Related U.S. Application Data

(62) Division of application No. 29/769,508, filed on Feb.
5, 2021, now Pat. No. Des. 947,630, which is a

Deuren s.c.

(57) **CLAIM**

The ornamental design for a wrench as shown and described.

DESCRIPTION

FIG. 1 is a front perspective view of the first embodiment of the claimed design;

FIG. 2 is a rear perspective view of the claimed design of FIG. 1;

FIG. 3 is a front view of the claimed design of FIG. 1;

FIG. 4 is a rear view of the claimed design of FIG. 1;

FIG. 5 is a left side view of the claimed design of FIG. 1;

FIG. 6 is a right side view of the claimed design of FIG. 1;

FIG. 7 is a top view of the claimed design of FIG. 1; and

FIG. 8 is a bottom view of the claimed design of FIG. 1.

FIG. 9 is a front perspective view of the second embodiment of the claimed design;

FIG. 10 is a rear perspective view of the claimed design of FIG. 9;

FIG. 11 is a front view of the claimed design of FIG. 9;

FIG. 12 is a rear view of the claimed design of FIG. 9;

FIG. 13 is a left side view of the claimed design of FIG. 9;

FIG. 14 is a right side view of the claimed design of FIG. 9;

FIG. 15 is a top view of the claimed design of FIG. 9; and,

FIG. 16 is a bottom view of the claimed design of FIG. 9. The broken lines shown are included for the purpose of illustrating portions of the wrench that form no part of the claim.

1 Claim, 10 Drawing Sheets

Related U.S. Application Data

division of application No. 29/670,466, filed on Nov. 15, 2018, now Pat. No. Des. 912,483.
